DESIGN FOR A BOTTLE CARRIER

Richard C. Marshall, Jr., Kansas City, Mo.

Application May 7, 1942, Serial No. 106,816

Term of patent 14 years

To all whom it may concern:

Be it known that I, Richard C. Marshall, Jr., a citizen of the United States, residing at Kansas City, in the county of Jackson and State of Missouri, have invented a new, original, and ornamental Design for a Bottle Carrier, of which the following is a specification, reference being had to the accompanying drawing, forming a part thereof.

Fig. 1 is a perspective view of the bottle carrier, showing my new design.

Fig. 2 is an edge elevational view thereof; and Fig. 3 is a top plan view thereof.

I claim:

The ornamental design for a bottle carrier, as shown.
